Primary Examiner — Susan Bennett Hattan*Assistant Examiner* — Janice Hallmark(74) *Attorney, Agent, or Firm* — Tim Tingkang Xia, Esq.;
Locke Lord LLP(57) **CLAIM**

The ornamental design for an atomizer, as shown and described.

DESCRIPTION

FIG. 1 is a front elevational view of an atomizer;
 FIG. 2 is a rear elevational view of the atomizer;
 FIG. 3 is a top plan view of the atomizer;
 FIG. 4 is a bottom plan view of the atomizer;
 FIG. 5 is a left side elevational view of the atomizer;
 FIG. 6 is a right side elevational view of the atomizer;
 FIG. 7 is a first perspective view of the atomizer;
 FIG. 8 is a second perspective view of the atomizer;
 FIG. 9 is a third perspective view of the atomizer; and,
 FIG. 10 is a fourth perspective view of the atomizer.
 The broken lines in the drawings depict parts of the atomizer
 that form no part of the claimed design.
